UNITED STATES PATENT OFFICE.

JOHN R. RICHARDSON, OF SCRANTON, PENNSYLVANIA.

COAL-SEPARATOR.

SPECIFICATION forming part of Letters Patent No. 655,580, dated August 7, 1900.

Application filed July 16, 1897. Serial No. 844,808. (No model.)

To all whom it may concern:

Be it known that I, JOHN R. RICHARDSON, a citizen of the United States, residing at Scranton, in the county of Lackawanna and State of Pennsylvania, have invented certain new and useful Improvements in Coal-Separators, of which the following is a specification, reference being had therein to the accompanying drawings.

10 My invention relates to coal-separators adapted particularly to separate the coal from flat slate and culm.

The invention consists in a rotary agitator fitted to a concave pocket in the form of a grating, the agitator being also provided with spaces adapted to permit of the discharge of the slate and culm to the refuse and saving the coal, which is of a different shape and is therefore not adapted to pass through the narrow openings, and this coal as it comes from the screen banks against the agitator. In the rotation of the agitator, which is in the form of a mutilated cylinder, the coal which has gathered in the pocket formed by the concave bottom of the grating and the cut-away part of the cylinder is elevated and carried over to the opposite side of the separator, the thin pieces of slate and culm dropping down through the spaces in the agitator and grating. The coal 25 then passes down to a raised grating, which elevates the coal and the remaining refuse, discharging the coal into an overchute, while the refuse passes down the main chute, where it may be subjected to the action of another 30 raised portion and overchute.

In the accompanying drawings I have shown, in Figure 1, a plan view of my separator, Fig. 2 being a section of the same.

The coal enters in the upper end of the 40 chute from the screen now in use, and it passes down the incline A to a more abrupt incline or dip B, made by a series of bars a, in the form of a grating, this grating connecting the inclines A and C. The spaces 45 between the grate-bars are sufficient to permit of the passage of slate and culm and refuse of this nature. In order to agitate the coal and refuse as it comes down the incline, and thus more perfectly separate it, I

provide an agitator D, located in proximity 50 to the grating and rotated by any suitable power.

The agitator is preferably composed of a shaft journaled in the side walls of the chute and a series of disks b, mutilated at opposite 55 points by having quarter-sections cutout, leaving spaces c. The disks are separated by spaces d, providing for the discharge of the culm and slate. These spaces are preferably wider than the spaces between the grate-bars, and 60 in order to prevent clogging I prefer to make the disks b with grooved peripheries e, adapted to closely fit the corresponding edges of the grate-bars, as shown at f. As the edges of the disks b project above the level of the 65 upper incline A, the coal and refuse banks against it; but as the agitator is rotated the cut-out portions form pockets into which the coal and refuse drop, the slate and culm passing through the spaces between the disks 70 and the grate-bars. In the rotation of the agitator the contents of the pocket remaining is carried over and discharged upon the incline C. At the bottom of this incline there is a second grating E, its bars being given 75 the form of a swell, and the end of the incline extends to an opening g, through which passes more of the refuse. As the mass slides up over the bent grate-bars E some of the refuse passes through which may have 80 passed the agitator and first grating and the clean coal bounds upwardly by reason of the shape of the grating E and is caught by an overchute F, located above the main chute and directly in line with the swell or curve 85 of the grating E, and the coal being lighter is elevated more than the refuse and is caught by the overchute, which carries it to a point of delivery, while the refuse which does not pass through the grating falls through the 90 opening g in the main chute. The overchute may be a single chute, or it may have a double discharge, a trough a' running off to each side.

What I claim is—

1. A coal-separator comprising an inclined chute, a concave grating connecting the upper and lower parts of the chute and a ro-

tary agitator located above the grating within the concavity and acting in connection therewith, substantially as described.

2. In combination with an inclined chute, a grating of concave form intermediate of the upper and lower sections of the chute and an agitator located in the concavity of the grating, said agitator being formed of a series of disks having a cut-away portion adapted to

elevate the coal and discharge the slate and culm through the openings in the agitator and grating, substantially as described.

In testimony whereof I affix my signature in presence of two witnesses.

JOHN R. RICHARDSON.
